(No Model.)

T. SHERRY.

CARRIAGE AXLE CUTTER.

No. 280,678.

Patented July 3, 1883.

UNITED STATES PATENT OFFICE.

THOMAS SHERRY, OF NEENAH, WISCONSIN.

CARRIAGE-AXLE CUTTER.

SPECIFICATION forming part of Letters Patent No. 280,678, dated July 3, 1883.

Application filed December 4, 1882. (No model.)

To all whom it may concern:

Be it known that I, THOMAS SHERRY, a citizen of the United States, residing at the city of Neenah, in the county of Winnebago and State of Wisconsin, have invented a new and useful Improvement in Carriage-Axle Cutters, of which the following is a specification.

My invention relates to improvements in carriage-axle cutters, in which rotary cutters, in connection with appropriate devices for securing the same to the axle and mechanism for feeding the cutters to the work to be performed, are employed to shorten the axles as their shoulders and the boxes of their wheels become worn, thereby obviating their excessive longitudinal movement, and dispensing with the washers usually employed for that purpose. I attain these objects by the mechanism illustrated in the accompanying drawings, in which—

Figure 1 is a side elevation of the entire machine as applied to a carriage-axle for operation thereon. Fig. 2 is a top view of the clamping mechanism, at the left of the line $x-x$ of Fig. 1, as applied to the axle for operation. Fig. 3 is a vertical section on the line $x-x$ of the same. Fig. 4 is a vertical section on the line $y-y$, Fig. 1, showing the cutting-tools in their application; and Fig. 5 is a vertical section on the line $z-z$, showing the feeding device.

Similar letters of reference indicate corresponding parts in the several views.

A represents a carriage-axle; EE, the clamps, by which is secured thereto the cutting mechanism; A' A', the bolts by which it is secured; C, a lug upon said clamps; B, a dog applied to the axle and said lug. L L L L represent round rods connecting plates F and I. K is a plate sliding loosely upon said rods. H H H H are bolts securing plate F to clamps E E. J is the crank-shaft, having the cutting-tools p and q at its extremity, and revolving in plates I and K. J' is the crank applied to shaft J. M M represent pinions, which are threaded internally, and are mounted upon the threaded studs m m. O is a pin or stud projecting from the crank-shaft J, and actuating the pinions M M.

The clamping device is placed upon the axle, as shown in Figs. 1 and 2, and secured thereto by the bolts A' A', and also, when necessary, by the application of the dog B over the lug

and back of the collar D upon the axle. The clamps E E are separate from the plate F, and secured thereto by bolts H H, said plate and the cutting mechanism connected with it by the bolts L L L L being adjustable in a horizontal plane with the axle by said bolts moving in the slots h h. Said clamps E E are tapering in the angular recess applied to the axle, corresponding with the taper of the axle, thus centering the plate F and the cutting mechanism connected thereto with the axle in a horizontal plane. The plate F is connected with plate I by the bolts L L and nuts l l. The crank-shaft J revolves in said plate I, and also in plate K, in which it is prevented from longitudinal movement by the shoulder k, the washer k', and the pin k''. The plate K is adapted for longitudinal movement upon the bolts L L. The pinions M M, through which pass the threaded studs m m, are threaded internally, one end of each stud being secured in plate K. The hubs of pinions M M are extended through plate I, upon the outside of which are collars n n, thereby retaining the pinions by their shoulders upon one side and the collars n n upon the other in their bearings in the plate I.

By revolving the shaft J, by means of the crank J', forward in the direction of the arrow, the pin O engages the teeth of pinions M M, revolving them upon the threaded studs m m, thereby forcing the plate K, and with it shaft J, carrying the cutters p q, longitudinally toward the axle and reducing its length, the cutter p cutting off a portion of its shoulder and q its extremity until the desired length is attained. The teeth of pinions M M are of sufficient width of face to allow the shaft J to be fed longitudinally toward the axle for the production of the desired length without the disengagement of the pin O and said teeth.

The cutting-tools are reeded by revolving the shaft J in the opposite direction; or, when pin O is not engaged with the pinions, it is more quickly accomplished by the operator revolving the pinions simultaneously with his fingers.

The adjustment of the tools p q is accomplished by moving them in their grooved bed nearer to or farther from the center of the tool-holder, in which they are secured by the bolts 1 2. This adjustment is made before the cut-

ting operation commences, after which the cutting proceeds, while the cutting-tool holder is feeding in a longitudinal direction, until the desired length is attained. The cutter *q* may 5 be so adjusted as to remove the material to the center of the axle, or a part only of it, and the remainder can be removed with a cold-chisel. When the required length is attained, the cutting apparatus is removed, and the thread 10 formed in the usual well-known manner.

Having thus described my invention, what I claim, and desire to secure by Letters Patent, is—

1. In an axle-cutter, the combination of the

tapered universal jaws, adjustable concentrically upon the axle, the adjustable revolving cutting-tools, feeding automatically in a direction longitudinal with the axle, and the feeding mechanism, substantially as described, and for the purpose as set forth. 15

2. The combination, with the tapered universal jaws, adjustable concentrically upon the axle, of the dog *B*, substantially as described, and for the purpose as specified. 20

THOMAS SHERRY.
